JOHN TAGGART, OF BOSTON, MASSACHUSETTS.

Design No. 3,463, dated April 27, 1869.

DESIGN FOR A GRATE-FORK.

The Schedule referred to in these Letters Patent and making part of the same.

To all persons to whom these presents may come:

Be it known that I, JOHN TAGGART, of Boston, in the county of Suffolk, and State of Massachusetts, have invented a new and ornamental Design, Form, or Configuration for Grate-Forks; and do hereby declare the same to be fully described in the following specification, and represented in the accompanying drawings, of which—

Figure 1 is a top view;

Figure 2, a bottom view; and

Figures 3 and 4, opposite side elevations of it.

In the construction of what are termed "grate-forks," two of the implements shown in the accompanying drawings are to be laid one against the other, and connected by a common centre-pin, going through the joint-part *a* of each, the same being as shown in Figure 5.

The inner face *b* of the joint is in a plane with the medial line of the series of prongs *cccc*. These prongs are curved, so that the series may form a concave claw *A*.

The shank *B* projecting from the claw, is curved between the joint-part and the claw.

It is also curved from the front-part to the handle-part *d*, which is convex transversely on its upper side, and concave transversely on its lower side, and has an elongated aperture, *e*, formed through, in manner as represented.

Figure 6 is a transverse section of the handle.

Figure 7, a transverse section of the shank between the handle and the joint-part.

Figure 8 is a transverse section between the joint-part and the claw.

Figure 9 is a transverse section of the series of prongs or the claw.

I claim as my invention, the design for a grate-fork substantially as above described, and as represented in the accompanying drawings.

JOHN TAGGART.
